LATCH

Lloyd L. Anderson and Robert E. Johnson, Grand
Rapids, Mich., assignors to Jervis Corporation,
Grandville, Mich., a corporation of Michigan

Application September 6, 1949, Serial No. 114,105

5 Claims. (Cl. 292—332)

1

This invention relates to a novel, useful and very practical latch which in use is primarily for releasably securing refrigerator doors in closed position. The latch is concealed, that is, it is installed between the inner and outer sides of the door adjacent its free vertical edge, the only part appearing outside the door being the handle, by means of which it is released from a keeper mounted on the refrigerator casing.

The present invention, in its general principle of operation, is similar to that shown in a pending application in the Patent Office, Serial No. 58,953, filed November 8, 1948, and owned by the same assignee. It, however, is an improved, simpler and more economical latch and less expensive to make, consisting of few parts which are easily fabricated and assembled, in which the spring force which is used to hold the door closed secures a tight sealing condition between the door and the refrigerator casing, insuring a minimum loss of refrigeration from within the refrigerator or introduction of heat therewithin which would occur if there was defective sealing. The latch also may be released whenever the door is to be opened without the necessity of using a heavy force by the one who operates the latch to release it.

An understanding of the invention having the desirable features and characteristics stated may be had from the following description, taken in connection with the accompanying drawings, in which,

Fig. 1 is a fragmentary horizontal section through the free edge portion of a refrigerator door and the adjacent casing showing the novel latch mechanism concealed in the door in its operative tripped position engaging with a keeper for the latch bolt mounted on the casing.

Fig. 2 is an elevation of the latch outside the door looking at it from the right in Fig. 1.

Fig. 3 is a section similar to Fig. 1 illustrating the latch mechanism in a cocked position, that is as it appears after it had been released from the keeper and remains in such released position, and with the latch about to be moved to closed position.

Fig. 4 is a section similar to Figs. 1 and 3, showing the operation of the latch mechanism and the position of the parts thereof in the case where the latch fails to remain cocked with the door open and has to be re-engaged with the keeper by a camming action thereagainst.

Like reference characters refer to like parts in the different figures of the drawings.

At the front of the side of the door casing where the free edge of a hinged door is to be re-

2

leasably secured, said casing being indicated at 1, a keeper is mounted. It includes an interiorly threaded sleeve 2 into which a threaded stem 3 of the keeper is screwed. At the outer end of the stem, in front of the adjacent casing, a generally triangular laterally extending bolt engaging head 4 is integrally formed which, at an outer corner, is cut away to provide an inclined surface. A relatively long screw 5 extends axially through the stem 3 and has a screw connection at its inner end for tightening and locking the keeper against change of position. The detail of the keeper is not further entered into as it is not a part of the present invention.

15 The latch mechanism of our invention is housed within the door 6 between its inner and outer sides adjacent its free vertical edge, it being understood that the door has a hinged connection to turn about a vertical axis adjacent its opposite vertical edge. The latch includes a supporting body of sheet metal having two spaced parallel sides 7 connected at one edge by an integral section 8 extending between them. At one end of each of the sides 7 is outwardly flanged and riveted or spot welded to a plate 9 which is located against the inner side of the outer covering member or face of the door 6, at the outer side of which a handle 11, pivotally mounted at one end on a pivot 12, is carried by the plate 10. The two plates 9 and 10 are securely connected together by screws as shown in Fig. 1. The handle is normally actuated by a spring 13 around the pivot rod 12, so that the handle when free to do so occupies an inner position generally paralleling the outer face of the door. The two plates 9 and 10 have openings 14 and 15 through them in alignment, and also in conjunction with an opening through the outer face of the door, through which a relatively long flat bar link 17 passes. A longitudinal slot 17a (closed at both ends) is formed in the outer end of said link 17. A vertically extending pin 16 which is carried by the handle a short distance from the pivot rod 12 passes through said slot 17a to eventuate the indicated connection between the handle and said member 17. A bracket or clip 18 is screw-connected to section 8 of the latch support at the inner end thereof and is held in place on the door by suitable screw connections as shown. The latter connections also secure a sheet member 19—having an opening therethrough—at the inner face of the free vertical edge portion of the door. The projecting keeper end 4 passes through the opening in member 19 to engage with the latch bolt carried on the fixed supporting structure housed within the door.

The latch bolt is formed from sheet metal and comprises two spaced horizontally-extending portions (one above and one below the mechanism associated therewith); said flat plate-like portions being connected adjacent one side of the latch bolt by the cross vertically disposed (when in place) web portion 21. A trip 22 comprises another vertically-extending cross connecting plate adjacent the opposite edge of said bolt member. When the door is moved towards closed position, the latch mechanism parts are located as shown in Fig. 3, the trip portion 22 being at such time caused to abut against the end 4 of the keeper, and continued movement actuates the bolt as hereafter described.

Arms integral with the sides 20 of the bolt extend inwardly between the parts 21 and 22, between and on which a transverse roller 23 is rotatably mounted on a pin which passes through the roller. Between the sides 20 of the bolt outwardly a short distance from the connecting section 21 a bar or pin 24 extends, which is secured at its ends to said bolt sides 20 having opposite parallel flat sides and opposite curved or arcuate edges as shown.

A pin 25 extends between the sides 7 of the support for the latch mechanism and is fixedly secured in place inwardly of the bolt. A link also of sheet metal having two parallel sides 26 connected by an integral cross piece 27 is mounted adjacent one end and near the part 8 on a pin or rivet 28 between the sides 7 of the support. The link extends to the inner end of the link bar 17, through which a pin 29 passes. On the pin 29 rollers 30 are mounted for rotation, one at each side of the inner ends of the sides 26 (Fig. 3).

The link bar 17, toward its inner end is widened, providing shoulders against which the inner end of a strong coiled compression spring 31 bears. The other end of the spring is against a support 32 therefor extending between and connecting 32 with the sides 7 of the main support. Such spring under compression tends to turn the link 26 counterclockwise. The rollers 30 at their peripheral edges are (when the latch is in locking, i. e., door-closing position) against the rounded edge of the pin or bar 24.

A torsion spring 33 is around the pin 25, one of the two end arms of such spring engaging against the inner side of plate 27 and the other abutting against a tongue 34 struck from one of the sides 20 of the latch bolt. It will be observed (Fig. 4) that the sides 20 of the latch bolt are recessed so that in the upper position of the bolt as in Figs. 1 and 3 pin 25 is in such recess to the bottom thereof, and provides a pivot support about which the bolt may rock. The effect of the torsion spring 33 on the bolt 28 is to turn it clockwise, when free to do so. Also in the lower edges of the sides 20 of the latch bolt an arcuate slot 29a is cut for receiving and guiding the latch bolt in its movements, the end of this slot acting as a stop in the tripped position as in Fig. 1. The latch bolt has substantially a floating movement between its two extreme positions of movement.

When the bolt is in its tripped position engaging with the keeper, as in Fig. 1, the heavy spring 31 exerts and transmits its force through rollers 30 against the rounded edge of the pin or bar 24, turning the latch bolt counterclockwise to bring the roller 23 against the inner side of the keeper head 4, the bolt turning about the axis of the pin 25. This causes the door to be held tightly closed and compress the usual gasket which is between the door and the door casing. On pulling

outwardly on the handle 11, link bar 17 is moved in the direction of its length, the link 26 is swung clockwise and the rollers 30 ride against the adjacent curved edge of the pin 24 and thence under it substantially as in Fig. 3, so that the outer flat side of the pin 24 comes against the inner edges or points of the rollers 30. The force of the spring 31 thereupon is transmitted to the pin 24 substantially through the center or axis of the pin 29, that is on dead center. The spring 33 thereupon is freed to exert its force to swing the latch bolt in a clockwise direction and disengage the roller 23 from its keeper. Because of said dead center position of the line of force of the spring 31, the bolt remains normally in its cocked position. On releasing the handle 11 it will return to inner position, pin 16 traversing the slot in the link bar 17, under the influence of the torsion spring 13.

With the latch in cocked position, on closing 20 the door the plate 22 of the bolt, with the bolt substantially as in Fig. 3, strikes against the end of the keeper 4, turning the bolt 20 about its pivot 25 and releasing it, the turning movement being in a counterclockwise direction, whereupon the 25 pin or bar 24 is swung to the right from the position in Fig. 3 to that in Fig. 1, the rollers 30 under pressure of spring 31 following the pin 24 and pressing thereagainst. The roller 23 is thereupon swung counterclockwise against the inner side of 30 the keeper head 4, with the spring 31 continuously exerting its force to cause the roller 23 to continuously press against the inner side of the keeper head.

As happens at times when the door is opened, 35 the latch through accident, inadvertence or otherwise, may not remain in its cocked position but will swing substantially to the position shown in Fig. 1 though away from and not engaged with the keeper. Under such conditions when the door 40 is closed the roller 23 rides upon the inclined outer corner portion of the keeper head 4, the latch bolt being cammed to the position substantially as shown in Fig. 4 until the roller 23 passes by the nose of the keeper head.

45 The structure described is relatively simple and inexpensive. It is economical to produce in large quantity production. With a spring force in the spring 31 substantially between a minimum of 24 pounds and a maximum of 40 pounds, the 50 maximum being obtained when the spring is most greatly compressed, the force required to trip the latch is approximately between four and seven pounds and substantially the same force exerted as a pull on the lever 11 releases the latch and 55 moves it to its released cocked position.

The invention is defined in the appended claims and is to be considered comprehensive of all forms of structure coming within their scope.

We claim:

1. In a latch structure, a support having spaced connected sides, adapted to be secured to and housed within a door adjacent a free edge thereof, a link bar located between the sides of the support extending outwardly beyond the outer end thereof adapted to have manually operable means connected therewith for moving the bar outwardly, a spring normally moving the link bar inwardly, a pin extending through the link bar at its inner end, a link through one end of which the pin extends pivotally mounted on the support adjacent its other end, a latch bolt having spaced connected sides located one at each side of said link and having arms extending therefrom, with a keeper engaging member at the outer ends of said arms, a second pin ex-

tending between the sides of the bolt, a third pin between the sides of the support spaced from and located inwardly from the first pin, and a spring carried on said third pin engaging at one end with said latch bolt and at the other end with the pivot pin upon which said link is mounted, said spring being of lesser strength than the first mentioned spring and normally acting to turn the latch bolt in the opposite direction from the movement of the latch bolt under the force of the first mentioned spring.

2. A structure as defined in claim 1, wherein said second pin has an arcuate shape peripheral portion against which the inner end of said link bears when the latch bolt assumes a keeper engaging position, and a flat peripheral portion against which the inner end of said link bar bears when the latch bolt assumes a keeper disengaging position.

3. A latch structure for use with a keeper and a door, comprising a support having spaced parallel sides connected along one edge and being disposed within the door and adjacent to the vertical edge of the latter, a manually adjustable link bar located between the sides of the support and extending outwardly therefrom beyond one end of the support and terminating at its outer end beyond the front of said door, a link pivotally connected to the inner end of the link bar and pivotally mounted on the support intermediate the sides thereof, a latch bolt having spaced interconnected parallel sides provided with a plurality of open end slots, a roller mounted on and intermediate the sides of the latch bolt and movable into and out of keeper-interlocking relation, a transverse pin interconnecting the sides of said latch bolt and having a flat peripheral portion and a curved peripheral portion, the curved peripheral portion of said pin bearing against the inner end of said link bar when said roller is in keeper-interlocking relation and the substantially flat peripheral portion of the pin bearing against the inner end of the link bar when the latch bolt assumes a position out of keeper-interlocking relation, a stud inwardly spaced from said pin and extending between and connected to the sides of said support and being disposed in one of said open end slots formed in said latch bolt, a torsion spring embracing said stud and biasing said latch bolt out of keeper-interlocking relation, and spring means of greater strength than said torsion spring cooperating with said link bar to effect biasing of said latch bolt into keeper-interlocking relation.

4. A latch mechanism for holding the free edge of a pivotally mounted door in closed position with respect to a cabinet by engaging a keeper mounted on such cabinet, comprising a housing for mounting on such door, a latch bolt pivotable with respect to said housing between a keeper engaging position and a cocked position, an elongated actuator member extending substantially in the direction of movement of said free edge of said door and movable with respect to said base in substantially the same direction, a guide member pivotally mounted at one end on said housing and pivotally connected at its other

end to the end of said actuator member extending inwardly toward such cabinet, the other end of said actuator member being engageable by an operating handle, said guide member being so oriented that said guide member and said actuator member form a substantially right angle construction, a pair of cooperating cam elements, one of said elements being mounted on said latch bolt and being arranged to move in an arcuate path as said latch bolt pivots between keeper engaging position and cocked position, the other of said cam elements being mounted on said right angle construction and being so arranged as to be movable toward and away from such cabinet with said actuator member, said other cam element lying in the path of said one cam element when said latch bolt is in keeper engaging position, said one cam element lying in the path of said other cam element when said latch bolt is in cocked position.

5. A latch mechanism for holding the free edge of a pivotally mounted door in closed position with respect to a cabinet by engaging a keeper mounted on such cabinet, comprising a housing for mounting on such door, a latch bolt pivotable with respect to said housing between a keeper engaging position and a cocked position, an elongated actuator member extending substantially in the direction of movement of said free edge of said door and movable with respect to said base in substantially the same direction, a guide member pivotally mounted at one end on said housing and pivotally connected at its other end to the end of said actuator member extending inwardly toward such cabinet, the other end of said actuator member being engageable by an operating handle, said guide member being so oriented that said guide member and said actuator member form a substantially right angle construction, a pair of cooperating cam elements, one of said elements being mounted on said latch bolt and being arranged to move in an arcuate path as said latch bolt pivots between keeper engaging position and cocked position, said one cam element having a flat surface and a convex surface, the other of said cam elements being a cam roller mounted on said right angle construction and being so arranged as to be movable toward and away from such cabinet with said actuator member, said cam roller lying in the path of said one cam element and engaging said convex surface thereof when said latch bolt is in keeper engaging position, said one cam element lying in the path of said cam roller and said flat surface engaging said cam roller when said latch bolt is in cocked position.
